UNITED STATES PATENT OFFICE.

JAMES E. McDADE, OF CHICAGO, ILLINOIS.

EDUCATIONAL-TEST DEVICE.

Application filed June 16, 1919. Serial No. 304,388.

To all whom it may concern:

Be it known that I, JAMES E. McDADE, a citizen of the United States, residing at Chicago, in the county of Cook and State 5 of Illinois, have invented certain new and useful Improvements in Educational-Test Devices, of which the following is a specification.

My invention relates to a device for 10 giving educational tests by means of which a set of test problems may be given to each student taking the test, the problems being concealed until a signal is given by the examiner to commence solving them, to ascertain 15 how proficient each student is in the subject forming the basis of the test.

In its preferred form my invention contemplates a holder under or in which the student may place a sheet of ordinary practice or working paper. The holder is 20 adapted to receive and hold a strip of cardboard on which the test problems are printed, the strip bearing the problems being placed in the holder so that the problems 25 will be concealed until a signal is given to the student to unmask the problems. The holder including a concealed set of problems is furnished to each student taking the test. After each student has written his or 30 her name and such other information as may be desired as, for example, the room and grade numbers and date on the sheet of working paper, and all students are ready for the test, the instructor gives the signal 35 to commence work. The devices are manipulated by the respective students so as to expose a set of problems and the students commence solving them and continue until the signal is given to stop, after which the 40 holders are again manipulated to conceal the problems. The devices and working papers are then collected. The bottom edge of the holder forms a guide for the student to follow so that the answers are all written 45 across the working paper on a straight line. The instructor has a key or answer card which may be placed alongside the student's 50 answers and the answers compared with the correct answers on the key card. Each student's paper is rated and the results of the test are tabulated on a score sheet and such information, for example, as the number of problems attempted by the student, the number answered correctly and the aver-

age percentage of the class quickly and conveniently obtained. 55

The principal object of my invention is to provide a novel device of simplified construction for use in an educational test system by means of which the test problems or 60 series of test problems are concealed until a signal is given by the examiner. The test problems preferably are printed on strips of paper and arranged so that they may be used over and over again. 65

A further object of my invention is to provide an educational test device by means of which the student may write the answers on ordinary practice paper, the edge of the holder forming a guide so that the student 70 may write the answers in a straight line across the sheet.

A further object of my invention is to provide an educational test device by means of which a series of tests may be given to 75 the student at one time, the arrangement preferably being such that only one of the series will be exposed at a time.

A further object of my invention is to provide novel means for checking the student's answers and for recording the results to ascertain information such, for example, as the average percentage of a class. 80

The invention consists of the novel and improved constructions, arrangements and 85 devices to be hereinafter described and claimed for carrying out the above stated objects and such other incidental objects as will appear from the following description. 90

The invention is illustrated in certain preferred embodiments in the accompanying drawings, wherein—

Fig. 1 is a perspective view of the preferred form of device for holding the student's working paper and for receiving and holding the test problems; 95

Fig. 2 is a perspective view of the preferred means for masking or concealing the test problems;

Fig. 3 is a plan view of the holder with the student's working paper and a set of problems in arithmetic in place on the holder, certain parts being broken away;

Fig. 4 is a plan view of the student's paper, 105 after it has been removed from the holder, showing the student's answers;

Fig. 5 is a plan view of the key or answer

card for the set of problems shown in Fig. 3;

5 Fig. 6 is a plan view of a preferred form of score sheet suitable for tabulating the results of a test with the key card attached to it by means of paper clips and with the student's paper in position for checking the student's answers;

10 Fig. 7 is a plan view of a color chart used in giving color tests;

Fig. 8 is a plan view of the key or answer card used in checking the student's answers to the color test;

15 Fig. 9 is a perspective view of a strip on which a map is placed for giving a test in geography, the map being folded over on the strip;

Fig. 10 is a plan view of an arrangement used in giving a test in geography;

20 Fig. 11 is a key or answer card used in connection with the test in geography;

Fig. 12 is a perspective view of a modified form of holder;

25 Figures 13 and 14 are perspective views illustrating fragmentary parts of another modified form of holder;

Fig. 15 illustrates another modified form of holder;

30 Figs. 16 to 19, inclusive, are perspective views of fragmentary parts of a strip adapted to be placed in the envelope shown in Fig. 2 to which are pasted a plurality of strips of paper on which are printed test problems illustrating how a series of prob-

35 lems may be given to the student at one time, the construction being such, however, that only one set of problems is exposed at one time;

40 Fig. 20 is a plan view of the back cover of a modified form of device comprising a plurality of leaves with a set of problems on each leaf by means of which a large number of problems may be given at one time; and

45 Fig. 21 is a fragmentary view of the device shown in Fig. 20 illustrating different sets of problems, only one being exposed at a time.

Like characters of reference designate 50 like parts in the several views.

Referring first to Figs. 1 to 6, inclusive, in which I have illustrated a preferred embodiment of my invention, it will be seen that the test device comprises a holder 25, a 55 sheet of paper 26 for the use of the student, a strip 27 on which a set of test problems is printed and the envelope 28 for concealing the problems until the signal is given. The parts preferably are all made of paper 60 or cardboard of suitable quality and thickness.

The holder 25 comprises a strip or base member 29 and the narrow end pieces 30 and 31 placed across and attached to the 65 strip 29. The end piece 30 is provided with

a recess 32 which is adapted to receive the left hand end of the strip 27 on which the test problems are printed, the sides of the recess preferably flaring outwardly to guide the strip 27 into place. The end piece 31 70 is provided with a slot 33 through which the right hand end of the envelope 28 marked α may be inserted. The holder, preferably, has printed thereon simple instructions as to the use of the device for the benefit of 75 the student. The envelope 28 is open at the left hand end and is adapted to receive the strip 27. The strip 27 is made somewhat longer than the depth of the envelope so that the left hand end of the strip will 80 project into the recess 32 when the envelope is in position on the holder. The envelope 28 is provided with a flap 34 which serves as convenient means for sliding the envelope back to expose the problems and 85 also as a stop. The holder is preferably made so that the distance between the inner sides of the end pieces 30 and 31 is eight and one-half inches so that an ordinary sheet of paper will just slip in between 90 them.

In giving a test, the holders are passed around one to each student in the room. Each student then places a piece of paper over the holder and writes his or her name, 95 and such other information as may be requested as his or her age, name of school, date, and room and grade numbers, across the top of the sheet as shown in Fig. 4. The envelopes 28 containing identical test 100 problems are then passed around, one to each student. Each student inserts the right hand end of the envelope through the slot 33 of the holder and the left hand end of the strip 27 in the recess 32. When the 105 signal to start is given, each student exposes the test problems, which may be done conveniently and quickly by holding the left hand end of the strip 27 and sliding back the envelope by taking hold of the flap 34. 110 Each student then endeavors to solve as many of the problems as possible before the signal to stop is given, writing the answers on the sheet of paper along the bottom edge of the holder. When the stop signal is 115 given each student pulls the envelope over the strip 27 to conceal the problems. The working papers are collected immediately and if no other tests are to be given the holders are also collected. The student's 120 answer papers are then ready for grading which may be done most conveniently by comparing each student's answers with the correct answers on the key card 35 illustrated in Figs. 5 and 6. The results of the 125 test may be found by using the score sheet 36 shown in Fig. 6.

The sheet is preferably ruled so as to provide a plurality of vertical columns 37 which register with the answers on the key card. 130

The sheet is divided into three parts, the upper part 38 having spaces for recording the number of "attempts" that is, the total number of problems attempted by each student, the middle part 39 having spaces for recording the total number of "rights" that is, the total number of problems answered correctly by each student, and the part 40 containing instructions concerning the use 10 of the score sheet and for certain data, for example, the number of the test and when and where it was given. The key card 35 has printed thereon the number of the test and the correct answers to the problems 15 given on the strip 27. The answers on the key card are numbered consecutively beginning at the left hand end of the card. The answers on the key card and the vertical columns on the score sheet are positioned so as 20 to register with the respective problems on the strip 27. The key card is preferably attached to the back of the score sheet by means of paper clips 41 so that the answers and the numbers of the problems will appear 25 at the top of the vertical columns 37 on the score sheet as shown in Fig. 6.

The score sheet and the key card attached thereto are placed on the desk and the instructor takes up each student's working 30 paper, one at a time, and compares the answers thereon with the answers on the key card and records the results on the student's paper and on the score sheet. The student's paper is shown placed above the key 35 card 35 in Fig. 6 ready for comparison. It will be noted that in the student's paper shown in Fig. 6 only eight problems were attempted and that problems numbered 3 and 6 were answered incorrectly which the 40 instructor records by placing a mark in column numbered 8 on the part 38 and another in column numbered 6 on the part 39 of the score sheet. The number of problems attempted and the number answered 45 correctly may be indicated on the student's paper for the benefit of the student. The score sheet preferably is ruled transversely to provide the spaces A, B, C, and D. The score sheet in Fig. 6 shows the score marks 50 for the papers of ten students. The marks scored in each column are totaled and the totals placed in space A under the respective columns and the totals of the columns placed in space E. The totals in space A 55 are each multiplied by the respective column numbers and the products placed in space B, the products being then added together and the total thereof placed in space F. The score marks showing the number of "rights" are added and multiplied in the same way using the spaces C and D and the grand totals are placed in the spaces G and H. If the computations have been made 60 correctly the total in space E will equal the total in space G. The percentage of ac-

curacy of the class equals the number of "rights" or the total in space H divided by the number of "attempts" or the total in space F which, for the markings shown on the sheet illustrated, is a little over 79. 70

In Fig. 7 I have illustrated a color card 42 which may be used in giving a color test in much the same way as an arithmetic test is given, the student being instructed to write the name of each color on his or her 75 working sheet. Fig. 8 shows a key card 43 for checking the answers in the color test which is used in the same way as the key card 35.

In Figs. 9 and 10, I have illustrated a map 44 mounted on a strip 45, the map being folded over as shown in Fig. 9 so it will pass into the envelope 28. The strip 45 may be provided with a flap 46 to guide the folded map into the envelope. The names of countries, rivers, cities, etc. are left off the map and instead each is given a number. On the lower portion of the map is printed the names of a number of countries, rivers, 85 gulf, etc. The student is expected to inspect the map and write the number given on the map on his or her paper underneath the respective countries, rivers, gulf, etc. In Fig. 11 is shown an answer card 47 for use in connection with the geography test. 90

In Fig. 12, I have shown a modified form of holder intended to be placed over the student's paper. The strip 27 bearing the test problems is held in place by tucking the upper corners thereof into the pockets 48 100 formed on the holder. The problems are concealed by means of a flap 49 hinged to one end of the device.

In Figs. 13 and 14, I have illustrated another modified form of holder comprising 105 an upper member 50 and a lower member 51 hinged together at one end. The student's sheet of paper 52 is placed between the members 50 and 51. The upper member 50 is provided with the pockets 53 into which the 110 upper corners of the strip 27 bearing the test problems may be tucked. When the holder is given to the student, the strip 27 is turned over to conceal the problems as shown in Fig. 13 and when the signal is given, the 115 student turns the strip right side up and places the upper corners thereof into the pockets 53 as shown in Fig. 14.

In Fig. 15, I have shown another modified form of device which is intended to be 120 placed over the student's paper. The test problems are printed on the lower member 54 and the upper member 55 serves to conceal the problems until the signal is given, the members being hinged together at one 125 end.

In Figs. 16 to 19, inclusive, I have shown a strip 56 to which are attached a plurality of strips as, for example, the strips 57, 58 and 59, each strip bearing a set of test prob- 130

lems. The strip 57 has a set printed on each side as shown in Figs. 16 and 17. When the strips are in the position shown in Fig. 16, they will slide into the envelope 28 (Fig. 2). 5 It will be noted from the drawings that the strip 58 is wider than the strip 57 and that the strip 59 is wider than the strip 58. The bottom edge of each strip serves as a guide for the student to follow in writing the 10 answers on a straight line across the sheet. It will also be noted that only one set of problems is exposed at a time.

In Figs. 20 and 21, I have shown a form 15 of test device intended more particularly for practice work. The device is in the form of a book and comprises a top member 60 and a bottom member 61 hinged together at one end with a plurality of leaves 62 in between, each bearing a set of test 20 problems. The bottom member 61 is provided with the flaps 63 and 64 under which the student's paper may be placed and held.

From the above it will be seen that the 25 test problems are concealed until a signal is given and that the student's paper is retained in position. The test problems may be easily and instantaneously exposed or unmasked as desired which gives the utmost precision in time tests. The first cost of the 30 device is not great and the cost of using the system is very low because the student's answers appear on lines close together and any ordinary paper may be used. The printed test cards are never written on and 35 may be used over and over again. The operation of the test device for various forms of tests is simple because the machinery of all, there being no new technique to master for each new test. A number of tests 40 may be given to the student at one time and he takes them up successively as called on and in the preferred form only one set of test problems is exposed at a time. A 45 large number of answers may be marked and scored rapidly and conveniently because it is necessary only to lay the key card along the student's answers and determine his standing by a rapid inspection. The 50 system of scoring enables the instructor to obtain very quickly information concerning the standing of the class as, for example, the average percentage of the class.

The system may be used in giving a "difficulty," "quantity," "accuracy" or "diagnostic" test. A "difficulty" test reveals how hard or how difficult a problem the student can master and in a test of this kind the problems are arranged on the card so that 55 they become increasingly difficult. A "quantity" test reveals how much work a student can do in a given time. With the device described the utmost precision in a test of this character, where time is of the essence, 60 is obtained because of the instantaneous

masking and unmasking of the problems. An "accuracy" test reveals how well a student does something he knows or should know how to do. A "diagnostic" test diagnoses each student's work and shows which 70 question or kind of questions the student fails to master. A device of this kind is particularly useful in showing up weak students in the class.

The word "problem" is used throughout 75 the specification and claims to apply to anything to which the student is to provide a correct solution or answer whether the subject is in arithmetic, geography or some other branch of education.

While I have described my invention in certain preferred embodiments it is realized that there might be considerable deviation from these constructions, arrangements, and devices without departure from the principles of my invention; therefore I do not wish to be understood as limiting the invention to the particular constructions, arrangements and devices shown except only 85 in so far as certain of the claims are so 90 limited.

I claim:

1. An educational test device comprising means bearing a plurality of associated strips of material each of which bears a set 95 of test problems, said strips extending longitudinally with respect to said means, means movable longitudinally with respect to said first mentioned means and adapted to expose or conceal said problems from view 100 when a signal is given, and means on which the answers to said problems may be written, said strips of material serving as guides to aid the student in writing the answers to the respective sets of problems in straight 105 lines across the sheet of paper.

2. An educational test device comprising means bearing a plurality of test problems arranged in vertical columns and adapted to be concealed until a signal is given, a sheet 110 of paper independent of the test problems but adapted to be placed adjacent thereto and on which the answers to the problems may be written in a straight line, and a key card bearing the correct answers to said 115 problems and adapted to be placed alongside the written answers on said sheet, for the purpose specified.

3. An educational test device comprising means bearing a plurality of test problems, 120 a sheet of paper independent of the test problems, means adapted to maintain said sheet of paper in a definite relationship with respect to the test problems, whereby the answers thereto may be written across the 125 sheet in a straight line, and a key card bearing the correct answers to said problems and adapted to be placed alongside the written answers on said sheet, for the purpose specified.

4. An educational test device comprising a strip bearing a set of test problems, a holder adapted to receive said strip and conceal the problems until a signal is given, a sheet of paper on which the student may write answers to the problems, said holder being adapted to hold said sheet of paper in alignment with said strip, and a key card bearing the correct answers to said problems against which the student's answers may be checked.

5. An educational test device comprising a strip bearing a set of test problems, a sheet of paper on which the student may write answers to the problems underneath each problem on said strip and a key card bearing the correct answers to the problems against which the student's answers may be checked, the answers on said key card being positioned so as to register with the respective problems on said strip.

6. An educational test device comprising a strip bearing a set of test problems, a holder adapted to receive said strip, a sheet of paper on which the student may write answers to the problems underneath each problem on said strip, and a key card bearing the correct answers to the problems against which the student's answers may be checked, said holder being adapted to hold said sheet of paper in alignment with said strip, the answers on said key card being positioned so as to register with the respective problems on said strip.

35 7. An educational test device comprising a strip bearing a set of test problems, a sheet of paper on which the student may write answers to the problems underneath each problem on said strip, a key card bearing the correct answers to the problems against which the student's answers may be checked, a score sheet provided with vertical column rulings on which the answers of each student in a class may be recorded, the answers on said key card and the column rulings on said score sheet being positioned so as to register with the respective problems on said strip.

8. An educational test device comprising a strip bearing a set of test problems, a sheet of paper on which the student may write answers to the problems underneath each problem on said strip, a key card bearing the correct answers to the problems against which the student's answers may be checked, the answers thereon being numbered consecutively, a score sheet divided by transverse ruling into two sections and provided with vertical column rulings on which the answers of each student in a class may be recorded, the answer on said key card and the column rulings on said score sheet being positioned so as to register with the respective problems on said strip so that the number of problems attempted by each student may be recorded in the proper column on

one section and the number of problems answered correctly by each student may be recorded in the proper column on the other section of said score sheet.

9. An educational device comprising a strip bearing a set of test problems, a sheet of paper on which the student may write answers to the problems underneath each problem on said strip, a key card bearing the correct answers to the problems against which the student's answers may be checked, the answers thereon being numbered consecutively, a score sheet provided with vertical column rulings on which the answers of each student in a class may be recorded, the answers on said key card and the column rulings on said score sheet being positioned so as to register with the problems on said strip and means for fastening said key card across the top of said score sheet so that the numbering of the answers on the key card will appear at the top of the respective vertical columns on said score sheet.

10. An educational test device comprising a holder for the student's working paper, a strip bearing a set of test problems and an envelope adapted to slide over said strip, said envelope being slidably retained on said holder.

11. An educational test device comprising a holder, a strip bearing a set of test problems and an envelope adapted to slide over said strip, said holder having means to retain a sheet of paper thereon and means whereby said envelope may be slidably retained thereon.

12. An educational test device comprising a holder, a strip bearing a set of test problems and an envelope adapted to slide over said strip, said holder having cross strips secured on the top thereof between which the student's working paper may be placed and means whereby said envelope may be slidably retained thereon.

13. An educational test device comprising a holder, a strip bearing a set of test problems and an envelope adapted to slide over said strip, said holder having cross strips secured on the top thereof between which the student's working paper may be placed, one of said cross strips having a slot adapted to receive the end of said envelope and the other cross strip having a recess adapted to receive one end of the strip bearing the test problems.

14. An educational test device comprising a holder, a strip bearing a set of test problems and an envelope adapted to slide over said strip, said envelope having a flap by means of which the envelope may be pulled backwardly through said slot to expose the test problems, said flap acting as a stop to prevent the envelope from being pulled entirely through the slot.

15. In an educational test device, the com-

5 combination with a holder and an envelope slidably retained thereon; of a strip adapted to slide into said envelope said strip having a plurality of flaps attached thereto, each of which bears a set of test problems, said flaps being arranged so that only one set 10 of problems will be exposed at one time.

16. In an educational test device, the combination with a holder and an envelope slidably retained thereon; of a strip adapted to slide into said envelope said strip having a plurality of flaps attached thereto, each of which bears a set of test problems, said flaps being folded over and arranged so that 15 only one set of problems will be exposed at a time.

17. In an educational test device the combination with a holder and an envelope slidably retained thereon; of a strip adapted to 20 slide into said envelope said strip having

a plurality of flaps attached to one side thereof each of which bears a set of test problems, said flaps progressively varying in length so that each flap when turned over, projects downwardly farther than the preceding one. 25

18. An educational test device comprising a holder for the student's working paper, a strip bearing a set of test problems, and an envelope adapted to slide relative to 30 said holder and over said strip, said strip being longer than the depth of said envelope and said envelope having a finger piece whereby said strip may be held stationary relative to said holder by placing a finger 35 of one hand on the projecting end of said strip while said envelope is moved relative to said strip by grasping said finger piece with the fingers of the other hand.

JAMES E. McDADE.
